CLAIM

The ornamental design for a magnetic sweeper, as shown and described.

DESCRIPTION

FIG. 1 is a perspective view of a magnetic sweeper embodying our new design;

FIG. 2 is a front view of the magnetic sweeper;

FIG. 3 is a rear view of the magnetic sweeper;

FIG. 4 is a right side view of the magnetic sweeper;

FIG. 5 is a left side view of the magnetic sweeper;

FIG. 6 is a top view of the magnetic sweeper;

FIG. 7 is a bottom view of the sweeper;

FIG. 8 is a perspective view of the magnetic sweeper shown in FIG. 1 with the arm in an extended position;

FIG. 9 is a perspective view of an alternate embodiment of the magnetic sweeper.

FIG. 10 is a front view of the magnetic sweeper in the alternate embodiment shown in FIG. 9;

FIG. 11 is a rear view of the magnetic sweeper in the alternate embodiment shown in FIG. 9;

FIG. 12 is a right side view of the magnetic sweeper in the alternate embodiment shown in FIG. 9;

FIG. 13 is a left side view of the magnetic sweeper in the alternate embodiment shown in FIG. 9;

FIG. 14 is a top view of the magnetic sweeper in the alternate embodiment shown in FIG. 9; and,

FIG. 15 is a bottom view of the magnetic sweeper in the alternate embodiment shown in FIG. 9.
